UNITED STATES PATENT OFFICE

102,003

DESIGN FOR A COMBINED LIQUOR CONTAINER CLUSTER AND SUPPORT THEREFOR

Carl Raetsch, Grunberg, Germany

Application August 8, 1935, Serial No. 58,006

Term of patent 3½ years

To all whom it may concern:

Be it known that I, Carl Raetsch, a citizen of the German State, residing at No. 6 Bismarckstrasse, Grunberg, Silesia, Germany, have invented a new, original, and ornamental Design for a Combined Liquor Container Cluster and Support Therefor, of which the following is a specification, reference being had to the accompanying drawing, forming part thereof.

In the drawing,

Fig. 1 is a perspective view of the combined liquid container cluster and support therefor showing my new design, and

Fig. 2 is a plan view thereof.

I claim:—

The ornamental design for a combined liquor container cluster and support therefor, as shown.

CARL RAETSCH.
